UNITED STATES PATENT OFFICE.

BENJAMIN H. JEFFERSON AND WALTER I. KIRK, OF CHICAGO, ILLINOIS, ASSIGNEES
TO LYON & HEALY, OF CHICAGO, ILLINOIS, A CORPORATION OF ILLINOIS.

PEDAL DEVICE FOR PIANOS AND OTHER PURPOSES.

1,374,891.

Specification of Letters Patent. Patented Apr. 12, 1921.

Application filed May 15, 1919. Serial No. 297,380.

To all whom it may concern:

Be it known that we, BENJAMIN H. JEFFERSON and WALTER I. KIRK, citizens of the United States, residing at Chicago, in the county of Cook and State of Illinois, have invented a certain new and useful Improvement in Pedal Devices for Pianos and Other Purposes, of which the following is a full, clear, concise, and exact description, reference being had to the accompanying drawings, forming a part of this specification.

Our invention relates to pedal devices, such as are used for pianos and for other purposes.

15 One of the objects of the invention is to provide a pedal device of the class mentioned which can be acted upon at a point or position above the one which is usually or normally acted or pressed upon.

20 Another object of the invention is to permit the pedal device to be operated by acting upon it at such usual or normal position, as well as at such elevated point or position.

25 Another object of the invention is to secure these pressing surfaces at different horizontal levels by means of a construction similar in general shape and character to the usual piano pedal.

30 Another object of the invention is to secure the different level pressing surfaces in a piano-pedal-like construction by adjustable devices contained largely within such construction.

35 Another object of the invention is to arrange for the easy, ready and quick adjustment of such relatively adjustable parts.

Another object of the invention is to secure simplicity and practicability of construction and operation.

Another object of the invention is to accomplish the foregoing and other desirable results in a simple and expeditious manner.

In the accompanying drawings Figure 1 is a front elevation of the lower part of the front of a piano provided with three pedal devices embodying our present invention;

Fig. 2 is a vertical section taken on line 2-2 in Fig. 1;

50 Fig. 3 is a cross section taken on line 3-3 in Fig. 2.

Referring to the drawings, we show a

portion of the front 1, of a piano provided with three pedal devices, 2, 3 and 4. The pedal devices 2 and 3 are in position to be 55 operated in the usual manner, that is by pressure or action upon pressing surfaces so located as to be readily available by a mature person of average size. The other pedal 4 is in condition to provide a surface 60 which can be acted or pressed upon in convenient manner by a child or other person having such short legs that they do not extend down to the pressing surfaces provided by the pedals 2 and 3 in the condition in 65 which said pedals are shown in Fig. 1.

The pedal devices 2, 3 and 4 are all alike, but the pedal devices 2 and 3 are shown in the first mentioned or normal condition or position, whereas the other pedal device 4, is 70 shown in the last mentioned or what may be called the abnormal condition or position.

Each of said pedals has a body or pedal member 5 preferably constructed with the usual upturned rear end portion 6 and a 75 toe portion 7. The latter in accordance with the present invention is made separable from the remainder of the member 3, the line of division being indicated at 8, (Fig. 2). This toe portion 7 is not only made separable, 80 but it is mounted upon a support 9 by which it may be held or supported in an upper position as shown in dotted lines in Fig. 2. The support 9 is preferably in semi-circular form and fits in a correspondingly 85 shaped groove 10 in the member 5. By giving the support 9 this shape, it can be readily accommodated inside of the member 5 because its end portion can be located inside of the upwardly extending end member 6. Thus the toe portion 7 when in its lowered position will, in connection with the body part 5, provide a pressing surface or surfaces which lie in the usual or normal position to permit of their being acted upon 90 by the foot of a mature person of average size playing the piano. Said toe portion 7, however, may be separated from the body part 5 and extended upwardly as shown in dotted lines in Fig. 2, and when in such 95 upward position it will provide an elevated pressing surface which may be contacted with and acted upon by the foot of a child or other short legged person playing the

90

95

100

piano. Thus the pedal device provides the pressing surfaces in the different horizontal positions, and this is accomplished by a pedal device of the usual size and character 5 of the ordinary piano pedal.

The toe piece 7 and part 5 may, if desired, be provided with a mortise and tenon joint, in which the tongue 12 is shown formed on the end of the toe piece 7 and the socket 10 for the same on the part 5. The toe piece 7 may be secured to the support 9 by means of a screw 13 passing through the end of the support 9 into the toe piece 7. The connection between parts 7 and 9, as well as 15 the screw 13, are concealed when the toe piece 7 is lowered and in contact with the body part 5.

Provision is made for holding or locking the toe piece 7 in its elevated position and 20 preferably in its lowered position also. The arrangement shown comprises a pin 14 passed downwardly into the body part 5 near the middle thereof and apertures 15 and 16 in the support 9. When the part 7 is lowered the pin 14 enters the aperture 15 and locks the support 9 and toe piece 7 in such lowered position. When said part 7 is elevated the pin 14 will enter the aperture 16 and thereby hold said part 7 in ele- 25 vated position. The head of the pin 14 projects above the top surface of the member 5 and consequently said pin may be lifted by the fingers and then allowed to drop into either one or the other of said apertures.

30 35 It will be understood that changes and

modifications may be made without departing from the spirit of the invention.

What we claim is:

1. A pedal device comprising a pedal member having its toe portion made separable from the body portion of said member, a rod or bar connected with said toe portion and serving to support the same in an elevated position, said rod or bar being arranged to slide in a groove formed in the 40 body portion of said member and to permit said toe portion to be separated from the latter and adjusted to an elevated position, and means for locking said rod or bar in adjusted position, said rod or bar being circular in form. 45

2. A pedal device comprising a pedal member having its toe portion made separable from the body portion of said member, a rod or bar connected with said toe portion and serving to support the same in an elevated position, said rod or bar being arranged to slide in a groove formed in the body portion of said member and to permit said toe portion to be separated from the 50 latter and adjusted to an elevated position, and means for locking said rod or bar in adjusted position, said rod or bar being circular in form, and said pin being arranged for vertical movement in said body portion. 55

In witness whereof, we hereunto subscribe our names this 24th day of April, A. D. 1919.

BENJAMIN H. JEFFERSON.
WALTER I. KIRK.
